WIRE FEEDING ATTACHMENT FOR WIRE STITCHING AND OTHER MACHINES

Original Filed Aug. 17, 1928

UNITED STATES PATENT OFFICE

RUDOLF E. ZERUNEITH, OF CAMDEN, NEW JERSEY, ASSIGNOR TO NEW JERSEY WIRE STITCHING MACHINE CO., OF CAMDEN, NEW JERSEY, A CORPORATION OF NEW JERSEY

WIRE FEEDING ATTACHMENT FOR WIRE STITCHING AND OTHER MACHINES

Original application filed August 17, 1928, Serial No. 300,244. Divided and this application filed June 26, 1930. Serial No. 463,843.

My invention relates to a new and useful wire feeding attachment for wire stitching and other machines of the type disclosed and claimed in my co-pending application Serial No. 300,244, filed August 17, 1928, of which the present application is a division.

In wire stitching and similar machinery, it is desirable to provide means for intermittently, synchronously, and automatically feeding the wire to the forming and driving mechanism of the wire stitching machine in predetermined lengths corresponding to the size of the staple or stitch to be formed, and to the above ends my invention consists of a pair of feed heads, means for driving said feed heads in timed relation to the forming and driving mechanism of the wire stitching machine, and adjustable means for predetermining the length of the wire to be fed with each stroke of the forming and driving mechanisms.

My invention further consists of various other novel features of construction and advantage, all as hereinafter described and claimed.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawings:

Fig. 1 represents a front elevation of the stitching head and wire feeding mechanism of a wire stitching machine embodying my invention.

Fig. 2 represents a section on line 2—2 of Fig. 1, certain parts being shown in elevation.

Fig. 3 represents a section on line 3—3 of Fig. 2.

Referring to the drawings, in which like reference characters indicate like parts, 1 designates the frame or housing of the stitching

head of a wire stitching machine embodying my invention, comprising the front and rear walls 2 and 3 and the end walls 4, said frame or housing being preferably made in two sections whose walls abut at 5, as will be understood from Fig. 2.

6 designates a main driving shaft which is journalled in suitable bearings 7 and having a hub which is secured to said shaft by the set screw 8. The shaft 6, through the link 9, connecting rod 10 and their adjuncts actuates the driver 11 and the former bar 12 to form and drive the staples or stitches from the wire 13 which is fed over and guided by the stationary cutter 14, the outer edge of which is in operative alignment with the movable cutter 15 whereby the desired length of wire may be severed before being bent by the former 12 and driven by the driver 11, the parts heretofore described forming part of my co-pending application above referred to and need not be described in greater detail, as the present invention is directed to the wire feeding mechanism.

The shaft 6 also carries a gear 17, which meshes with the gear 18 on the shaft 19, having a hub which is secured to said shaft by the set screw 20 and which carries at its front or outer end the feed head 21. The gear 18 meshes with the gear 22 on the shaft 23 having a hub which is secured to said shaft by the set screw 24 and which carries at its front end the feed head 26. The revolution of the gear 17 on the shaft 6 in the direction of the arrow 27 imparts a rotary motion to the gears 18 and 22, and consequently the shafts 19 and 23 and the feed heads 21 and 26, in the direction of the arrows 28, as will be understood from Fig. 1.

The wire 13 is propelled by means of the juxtaposed feed heads 21 and 26, which are provided with the spring jaws 29 and 30 which are formed by cutting the slots 32 and the enlarged inner openings 33 whereby a certain amount of resiliency is imparted to said jaws. The slots 32 in the feed heads 21 and 26 are positioned in opposite directions, as seen in Fig. 1, so that the free end of the jaw 29 is juxtaposed to the fixed and connected portion of the jaw 20 and vice versa. The

outer working peripheries 34 and 35 of the jaws 29 and 30 are cylindrical or concentric about the axes of the shafts 19 and 23, and so spaced as intermittently to engage the opposed faces or surfaces of the wire 13, to propel the latter in the direction of or towards the cutting, forming and driving means shown in the right hand side of Fig. 1. The resiliency of the jaws 29 and 30 permits of the insertion therebetween of wires 13 of various thicknesses, without the necessity of adjustment, and since the wire 13 is only propelled when the opposite faces thereof are intermittently engaged by the peripheral juxtaposed contact or working faces or areas of the jaws 29 and 30, it follows that the length of wire propelled or fed by each revolution of the shafts 19 and 23, is predetermined by the peripheral contact of said jaws, the maximum length of wire fed by a single revolution of the shafts 19 and 23 obviously being equal to the length of the periphery 34 or 35 of the jaws 29 and 30. This maximum length of wire is only fed or propelled when the jaws 29 and 30 are in direct opposition so that the entire length of their peripheries 34 and 35 will contact with the wire 13 simultaneously, and by varying the angular relation of the jaws 29 and 30, and hence the contacting peripheral areas of said jaws, the length of the wire fed or propelled by a single revolution of the shafts 19 and 23 is varied accordingly. The shaft 23 is retained by means of the latch 38 which engages an annular groove 43 in the rear end 39 of said shaft, see Fig. 3, and when it is desired to adjust the relation of the jaws 29 and 30, it is merely necessary to raise the latch 38 and move the shaft 23 longitudinally until the gear 22 is out of mesh with the gear 18, whereupon said shaft may be revolved to the desired extent and then restored to the position seen in Fig. 2. When the desired adjustment has been secured, the shaft 23 is withdrawn rearwardly until the gear 22 is again in mesh with the gear 18 and the latch 38 is again engaging the groove 43 in the rear end 39 of said shaft. By so adjusting the relation of the shafts 19 and 23, the extent or length of the contact of the peripheries or working faces 34 and 35 of the jaws 29 and 30 is predetermined, thereby to predetermine the length of the wire 13 fed or propelled by a single revolution of the shafts 19 and 23. The wire 13 is guided in suitable guide tubes or channels 39 and 41 suitably supported in the studs or lugs 44 carried by the front 2 of the casing 1.

Since the wire 13 is only fed or propelled when the peripheries 34 and 35 of the jaws 29 and 30 are in contact, it will be seen that the wire is fed intermittently and automatically, and that by properly timing or synchronizing the revolutions of the shafts 19 and 23, by proper selection of the gears 17,

18, and 22, the length of the wire fed and the frequency of its intermittent propulsion can be controlled and predetermined in accordance with requirements of the cutting, forming, and driving operations. The hubs of 70 the feed heads 21 and 26 are retained on the shafts 19 and 23 by set screws 42, whereby further adjustment of the relative positions of said heads may be obtained.

It will be understood that while I have 75 described my invention as being a division of my copending application aforesaid and as being especially adapted to wire stitching machines, the broad principles of my invention are equally adaptable to any other machine, wherein it is desired to feed or propel a wire intermittently to any desired mechanism for any desired purpose.

It will be further apparent that while I have shown spur gears 17, 18 and 22 as being 85 employed for the actuation of the rotary jaws, any other suitable form of power transmission device may be employed, as spiral, bevel or other form of gearing, without departing from the spirit of my invention. 90

I am aware that the invention may be embodied in other specific forms without departing from the spirit or essential attributes thereof, and I therefore desire the present embodiment to be considered in all respects 95 as illustrative and not restrictive, reference being had to the appended claims rather than to the foregoing description to indicate the scope of the invention.

Having thus described my invention, what 100 I claim as new, and desire to secure by Letters Patent, is:

1. A feeding mechanism comprising a pair of opposed one-piece, resilient rotary jaws each having a periphery less than a complete 105 circle; said jaws being adapted to coact and to grip and propel the material fed therebetween, and means for varying the overlap of said jaws.

2. A feeding device, comprising a pair of 110 juxtaposed shafts, means to revolve said shafts in timed relation to each other, a feeding head carried by each of said shafts in operative alignment with each other, said feeding heads each comprising a resilient 115 one-piece jaw having an outer circular peripheral portion adapted to coact with the corresponding outer circular peripheral portion of the other resilient jaw to grip and propel the material fed therebetween, and 120 means for varying the angular relation of said feeding heads and the overlap of said jaws.

3. A feeding device, comprising a pair of 125 juxtaposed shafts, means to revolve said shafts in timed relation to each other, a feeding head carried by each of said shafts in operative alignment with each other, said feeding heads each comprising a resilient jaw having an outer circular peripheral portion 130

adapted to coact with the corresponding juxtaposed outer circular peripheral portion of the other resilient jaw to grip and propel the material fed therebetween, and means for varying the angular relation of said feeding heads and the overlap of said jaws, said means including a train of gears interconnecting said two shafts, the gears of said train being adapted to be displaced axially so as to throw the same out of mesh and into mesh in any desired angular relation to the remaining gears.

4. A feeding device, comprising a pair of juxtaposed shafts, means to revolve said shafts in timed relation to each other, a feeding head carried by each of said shafts in operative alignment with each other, said feeding heads each comprising a resilient jaw having an outer circular peripheral portion adapted to coact with the corresponding juxtaposed outer circular peripheral portion of the other resilient jaw to grip and propel the material fed therebetween, and means for varying the angular relation of said feeding heads and the overlap of said jaws, said means including means for adjustably securing said feeding heads to said shafts.

5. In a feeding device, a casing, a shaft journalled in said casing having its front end projecting through the front wall of said casing, a gear fast on said shaft, means for revolving said gear, a second shaft journalled in said casing parallel to said first shaft and having its front and rear ends projecting through the front and rear walls of said casing, a gear fast on said second shaft and normally in mesh with the gear on said first shaft, feeding heads on the juxtaposed front ends of said shafts, and a latch pivoted to the rear of said casing and engaging a seat in the rear end of said second shaft whereby the latter is retained in normal operative position with respect to said first shaft.

6. In a feeding device, a casing, a shaft journalled in said casing having its front end projecting through the front wall of said casing, a gear fast on said shaft, means for revolving said gear, a second shaft journalled in said casing parallel to said first shaft and having its front and rear ends projecting through the front and rear walls of said casing, a gear fast on said second shaft normally in mesh with the gear on said first shaft, a latch pivoted to the rear of said casing and engaging a seat in the rear end of said second shaft whereby the latter is retained in normal operative position with respect to said first shaft, and a pair of feeding heads adjustably carried by the front ends of said shafts, each comprising a resilient jaw having a circular periphery, said jaws being adapted to grip and propel the material disposed between said feeding heads through a distance equal to the length of their contacting circular peripheries.

7. In a feeding device, a casing, a shaft journalled in said casing having its front end projecting through the front wall of said casing, a gear fast on said shaft, means for revolving said gear, a second shaft journalled in said casing parallel to said first shaft, and having its front and rear ends projecting through the front and rear walls of said casing, a gear fast on said second shaft normally in mesh with the gear on said first shaft, a latch pivoted to the rear of said casing and engaging a seat in the rear end of said second shaft whereby the latter is retained in normal operative position with respect to said first shaft, a pair of feeding heads adjustably carried by the front ends of said shafts, each comprising a resilient jaw having a circular periphery, said jaws being adapted to grip and propel the material disposed between said feeding heads through a distance equal to the length of their contacting circular peripheries, and means for predetermining the length of material fed by a single revolution of said heads.

8. In a feeding device, comprising a pair of juxtaposed shafts, means to revolve said shafts in timed relation to each other, a feeding head carried by each of said shafts in operative alignment with each other, said feeding heads comprising a resilient jaw having an outer circular peripheral portion adapted to coact with the corresponding peripheral portion of the other resilient jaw to clamp the material fed therebetween, and means for varying the angular relation of said feeding heads and overlap of said jaws, said means consisting of gearing mounted on the juxtaposed shafts.

9. A feeding mechanism comprising a pair of feed rolls or feeding cams mounted upon a pair of juxtaposed shafts in operative alignment with each other, means to revolve said shafts, and means to vary the contacting surface of said feed rolls or cams which clamp the material fed therebetween, said means consisting of gearing mounted on the juxtaposed shafts, whereby the length of material fed may be varied while the feeding mechanism is in motion.
